UNITED STATES PATENT OFFICE

2,234,106

WINDOW SHADE ATTACHMENT

Milton A. Bowerman, Seattle, Wash.

Application August 2, 1939, Serial No. 288,039

2 Claims. (Cl. 156—31)

My invention relates to new and useful improvements in window shade attachments and has as one of the principal objects thereof the provision of an attachment or device which may be readily attached to the lower end of a window shade without necessitating the usual stitched hem in the latter, which may be employed in connection with any type of window shade, which may be secured or removed without damage to the window shade, even by unskilled persons, and whereby the reversal of the window shade may be conveniently effected.

Another object of my invention is to provide a device of the above described character which may be readily attached to window shades already in use without modifying the latter and to window shades in which the hem portion has been severed or partially severed therefrom.

A further object of my invention is to provide a device of the above described character which is simple in construction, durable in use, efficient in operation and economical in manufacture.

Other objects and advantages will be apparent from the following description, appended claims and annexed drawing.

Referring to the drawing wherein like reference characters designate like parts throughout the several views:

Figure 1 is an elevation of a window shade illustrating my invention as applied thereto.

Figure 2 is a detail sectional view, on an enlarged scale, taken on the line 2—2 of Figure 1 and illustrating my invention in attached condition to a shade.

Figure 3 is a view similar to Figure 2 but illustrating my invention in condition for removal from or attachment to a shade.

In practicing my invention, as illustrated in the drawing, I provide a window shade 5, the upper end (not shown) being attached to a shade roller 6. The lower end section 7 of the shade has attached thereto my improved form of window shade attachment 8, the latter comprising an elongated relatively thin resilient body inflected between its side edges to define adjacently disposed side walls 9 and 10. The side wall 9 is formed with a longitudinally extending upper edge section 11 bent upon itself as at 12 and terminating in a beaded portion 13 disposed away from its wall 9. The side wall 10 is formed with a longitudinally extending intermediate section 14 having a portion 15 bent upon itself and terminating in a loop 16 fashioned with a lengthwise extending edge section 17 disposed in prox-

imity to the section 11 for clamping therebetween a portion of the lower end section of the shade 5. The loop 16 defines a lengthwise extending channel 18 in which the portion 13 extends a sufficient distance to coact with the wall of the channel to cohibit movement of the walls 9 and 10 in a direction away from each other. When the portion 13 is thus disposed within the channel 18 the intermediate section 14 coacts with the wall 9 to clamp an adjacent portion of the shade 10 5 therebetween. The lower side edge of the body has swiveled thereto an eye 19 to which is attached a shade raising and lowering cord 20 whereby said shade may be operated.

From the foregoing it will be apparent that 15 when the walls 9 and 10 are urged in a direction away from each other, the lower edge section of the shade 5 may be inserted therebetween as clearly illustrated in Figure 3 of the drawing. When the lower edge section of the shade is thus 20 inserted between the walls 9 and 10, said walls are moved in a direction towards each other causing the beaded portion 13 to snap into the channel 18 and effect clamping of adjacent portions of the shade between the sections 11 and 17 and the section 14 and wall 9 subjacent the section 11 respectively, thereby providing an attachment by which the lower non-selvedge edge of the shade is protected from raveling and for 25 operating the shade. 30

It is obvious that the invention is not confined to the herein described use therefor as it may be utilized for any purpose to which it is adaptable. It is therefore to be understood that the invention is not limited to the specific construction as illustrated and described, as the same is only 35 illustrative of the principles of operation, which are capable of extended application in advance forms, and that the invention comprehends all 40 construction within the scope of the appended claims.

What I claim is:

1. In a device of the character described, comprising an elongated relatively thin resilient body portion having its upper edge bent inwardly and downwardly and turned upwardly to form a beaded portion, the lower edge of the body portion bent upwardly to a point opposite to the beaded portion of the downwardly turned portion, the upper edge thereof turned downwardly and upwardly and flared outwardly, whereby when a piece of fabric is placed between the lower edge of the downwardly bent portion and the upper edge of the upwardly bent portion the fab- 50 55

ric is clamped at three distinct points when the loop portions are snapped together.

2. In a device of the character described comprising an elongated relatively thin body portion having its upper edge bent inwardly and downwardly, the lower edge of the body portion bent upwardly to a point opposite the lower edge of the downwardly turned portion, the upper edge

thereof turned downwardly and upwardly and flared outwardly, whereby when a piece of fabric is placed between the lower edge of the downwardly bent portion and the upper edge of the upwardly bent portion, the fabric is clamped at three distinct points when the loop portions are snapped together. 5

MILTON A. BOWERMAN.
